FIG. 1 is a top, right, front perspective view of an electrical connector according to our design;
FIG. 2 is a bottom, left, rear perspective view thereof;
FIG. 3 is a front elevation view thereof;
FIG. 4 is a left side elevation view thereof; and
FIG. 5 is a rear elevation view thereof.
FIG. 6 is a right side elevation view thereof;
FIG. 7 is a top plan view thereof; and,
FIG. 8 is a bottom plan view thereof.

The broken line portion of the figure drawings is included to show unclaimed subject matter only and forms no part of the claimed design. The dot-dash line in the figure drawings represents the boundary of the claimed design.

In a preferred embodiment, the nature of this product is an electrical connector that is configured to electrically connect to a pair of electrical devices.
